REFINING MACHINE FOR COCOA-CONTAINING AND LIKE MASSES

Richard Goll, Dresden, Germany

Application June 22, 1938, Serial No. 215,311
In Germany July 5, 1937

2 Claims. (Cl. 99—236)

The invention relates to a device in refining machines for improving cocoa-containing masses, such as preferably chocolate- and cocoa-masses, which under continuous subdivision into very large surfaces are subjected to the action of the treating air, the working bodies being moved to and fro or in circulation. Such machines are known per se. In these known refining machines with reciprocating as also with spinning rotating working bodies the particles in the interior of the mass are continuously brought to the surface and thus into contact with the treating air. It has however been found that cocoa-containing masses are best improved in taste when they are subjected with the maximum surface to the action of air. For this purpose it has already been attempted to spray the mass through nozzles or lead it through comparatively narrow blade wheels from the inside and throw it off, but with these devices a fine and uniform distribution of the mass over a large air-filled chamber has not been obtained. Moreover, with these devices difficulties in operation arise, due to the toughness or the fluidity of the mass.

In order to obtain with the before-mentioned refining machines a really effective aeration of the mass with removal of the substances adversely affecting the aroma in the minimum time, according to the invention there is arranged over the receptacle containing the mass in the refining machine a roller set in rapid rotation and preferably fitted with a plurality of blades 1^* , spraying rings, pins or the like distributed uniformly over its surface, which breaks up the mass elevated from the receptacle of the refining machine and led over its whole length through a distributing pipe from the interior or in a broad band from the exterior and throws it in finely divided condition in all directions through the space above the receptacle filled with constantly renewed treating air. For guiding the mass in a broad band from the exterior the core of the roller is preferably hollow and provided with numerous openings $1a$ for the outlet of air or other gases, which is sucked in automatically or supplied by a separate blower to the hollow core of the roller.

In order to explain the invention one embodiment of the device applied to three different refining machines is illustrated diagrammatically in the drawing, in which

Fig. 1 is the device in a refining machine with a reciprocating runner.

Fig. 2 shows the device in a refining machine having a spinner rotating about a vertical axis as the working body, and

Figs. 3 and 4 show in vertical longitudinal section and in cross section the device in a refining machine having a drum rotating about a horizontal axis and a rotating blade mechanism with a horizontal shaft.

Fig. 5 is an enlarged section of the roller 1 taken on the line V—V of Fig. 1 looking in the direction of the arrows.

In Figs. 1 to 4 is shown a rapidly rotating roller 1 with a plurality of blades 1^* uniformly distributed over its surface and extending over its whole length, which blades 1^* are turned up at their edges to increase the ability to take up the mass supplied thereto. In the device shown in Figs. 1 and 2 the cocoa-containing mass is elevated from the receptacle 2 or 3 of the refining machine through a pipe 5 by means of a pump 6 into a distributing pipe 7 , which is arranged in the present instance over the roller 1 . From the distributing pipe 7 the mass flows in a broad band from the outside on to the roller 1 . In the device shown in Fig. 1 the oscillating kneading roller 9 is moved through the mass by any well known or approved means not shown. In the device shown in Figs. 3 and 4 the pipe 5 and the pump 6 are replaced by the inner wall of the rotating drum 4 , the lower part of which acts as a collecting receptacle for the cocoa-containing mass. This revolving drum 4 is used instead of the receptacles 2 and 3 and is rotated in the direction of the arrow in Fig. 3 by any well known or approved means not shown. Said drum 4 is, as stated, a substitute for the pump device 6 (see Figs. 1 and 2) inasmuch as the drum lifts the chocolate mass upwards on its side during rotation, as shown in Fig. 3.

It will be understood that the mixing and kneading device in this instance may be of any well known or approved type such as the revolving wing device shown in Fig. 3. In this instance a stripper blade 8 is used for the distributing pipe 7 , which allows the mass elevated and stripped off from the inner wall of the drum 4 to flow to the roller 1 in a broad band also from the outside. As is clear from Fig. 3 the mass is thrown off by the roller 1 over its whole length in finely divided condition through the space within the drum 4 filled with fresh air.

In the device in the refining machine shown in Figs. 1 and 2 catch plates which are sometimes necessary at a greater distance from the roller 1 above the receptacle 2 and 3 are not shown. Where the receptacle is of sufficient length, catch plates can be entirely dispensed with.

What I claim is:

1. In a machine of the character described, an aerating device, means for supplying a cocoa-containing mass to said aerating device in a pre-determined direction, means for catching the aerated cocoa-containing mass and returning it to the supplying means, said aerating device comprising a hollow perforated distributing roller having its axis approximately normal to the direction of supply and provided with radial blades, a source of supply of aerating gas attached to said hollow roller, and means for rotating said aerating means.

2. In a machine of the character described, an

aerating device, means for supplying a cocoa-containing mass to said aerating device in a pre-determined direction, means for catching the aerated cocoa-containing mass and returning it to the supplying means, said aerating device comprising a hollow perforated distributing roller having its axis approximately normal to the direction of supply and provided with radial blades concave towards the direction of their rotation, a source of supply of aerating gas attached to said hollow roller, and means for rotating said aerating means.

RICHARD GOLL.
